Primary Examiner — Keli L Hill(74) *Attorney, Agent, or Firm* — Quickpatents, LLC; Kevin Prince(57) **CLAIM**

The ornamental design for a hair clip, as shown and described.

DESCRIPTION

FIG. 1 is a perspective view of a hair clip, showing my new design in a closed position;

FIG. 2 is a right-side elevational view of FIG. 1;

FIG. 3 is a left-side elevational view of FIG. 1;

FIG. 4 is a front elevational view of FIG. 1;

FIG. 5 is a rear elevational view of FIG. 1;

FIG. 6 is a top plan view of FIG. 1;

FIG. 7 is a bottom plan view of FIG. 1;

FIG. 8 is a perspective view thereof, illustrated in an open position; and,

FIG. 9 is a right-side elevational view of FIG. 8.

The dot-dot-dash broken lines represent the bounds of the claimed design while all other broken lines are included for the purpose of illustrating portions of the hair clip; the broken lines form no part of the claimed design.
